DESIGN FOR AN ATOMIZING DEVICE

Frederic A. Vuillemenot, Toledo, Ohio, assignor
to The De Vilbiss Company, Toledo, Ohio, a
corporation of Ohio

Application March 9, 1939, Serial No. 83,478

Term of patent 7 years

To all whom it may concern:

Be it known that I, Frederic A. Vuillemenot, a citizen of the United States and resident of Toledo, in the county of Lucas and State of Ohio, have invented a new, original, and ornamental Design for an Atomizing Device, of which the following is a specification, reference being had to the accompanying drawing, forming a part thereof.

In the drawing Figure 1 is a side elevational view of an atomizing device showing my new design; Figure 2 is a front elevation thereof.

The essential feature of my new design resides in the portions shown in full lines.

I claim:

The ornamental design for an atomizing device, substantially as shown and described.

FREDERIC A. VUILLEMENOT.
